UNITED STATES PATENT OFFICE

DORIS V. BELKNAP, OF BRONXVILLE, NEW YORK, ASSIGNOR TO MONUMENT MILLS, OF HOUSATONIC, MASSACHUSETTS, A CORPORATION OF MASSACHUSETTS

DESIGN FOR TEXTILE FABRIC

Application filed May 8, 1930. Serial No. 35,545. Term of patent 3½ years.

To all whom it may concern:

Be it known that I, DORIS V. BELKNAP, a citizen of the United States, residing at 15 Merriam Avenue, Bronxville, county of Westchester, and State of New York, have invented a new, original, and ornamental Design for Textile Fabric, of which the following is a specification, reference being had to the accompanying drawing, forming part hereof.

The drawing is a plan view of a piece of textile fabric showing one complete unit of the design, which unit is repeated over the surface of the fabric in successive relation.

I claim:

The ornamental design for textile fabric as shown and described.

DORIS V. BELKNAP.
